UNITED STATES PATENT OFFICE.

WILLIAM C. KRAUSE, OF MILWAUKEE, WISCONSIN.

BOTTLE-CRATE CORNER IRON.

Application filed September 27, 1926. Serial No. 138,008.

This invention pertains to improvements in corner irons for bottle cases, crates, and the like, and has primarily for its object to provide a simple, inexpensive and efficient corner iron, which will effectively reinforce the corner of a case or crate, and enable ready and secure stacking of the same one upon the other.

A further object resides in the provision of a one piece corner iron stamped from sheet material and adapted to efficiently protect the top, bottom and corner edges of a wooden crate, as well as to reinforce the same and to securely hold the sides together without strain or dependence upon the securing rivets.

With the above and other objects in view, which will appear as the description proceeds, the invention resides in the novel construction, combination and arrangement of parts substantially as hereinafter described, and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

Figure 1 is a vertical sectional view through a portion of a crate or case, with the present invention attached thereto, and

Figure 2 is a sectional view taken on the line 2—2 of Figure 1.

As explained in the preceding objects, the present invention is designed particularly for use in connection with wooden cases or crates commonly employed for holding milk bottles, or the like, such as disclosed in my Patent No. 933,184, wherein the corner irons are secured to the interior of the crate. Inasmuch as crates of the general character are subjected to exceptionally rough handling, it is essential that the same be properly reinforced at their corners and edges, as well as being provided with means to effect a secure stacking of the crates one upon the other.

Heretofore this has been accomplished in various ways, which, due to complicated structures, are more or less expensive, and in other instances present objections due to the fact that as the rivets or securing means become loosened or sheared off, or the sides of the box become split laterally, the irons be-

come loose or detached from the crate and fail to properly serve their function.

The present invention, which claims to overcome all of the objections heretofore encountered, comprises a corner angle iron 1, the sides 2 of which are bent at right angles to one another to enclose the corner of the crate 3, which is constructed of wood and has an open top and bottom, as disclosed in the patent referred to. While the bottle holding means is not illustrated in the present instance, it is obvious that any structure may be employed for this purpose, such as that disclosed in my earlier patent.

Extending laterally from the top and bottom of the iron 1 are the flanges 4, which engage the top and bottom edges of the crate 3, and protect the same against splintering, as well as to reinforce the sides and hold them together in instances where they become split horizontally. The top flange 4 is provided with an inwardly offset projection 5, which extends upwardly for the purpose of interengaging the lower edge of an adjacent crate stacked thereon.

Both the top and bottom flanges are provided with depending ears 6 bent parallel to the sides 2 and engaging the interior of the sides of the crate 3. While the foregoing structure is of such nature that when the corner irons are fixed upon the crate and the ears 6 are bent down against the inner sides of a crate, the corner iron will be securely attached to the same. It is further desired to more securely attach the iron to the crate, and therefore rivets 7 are employed which pass through the sides 2 of the iron, the sides of the crate and of the ears 6. In addition to the foregoing, rivets may be spaced at any desirable intervals intermediate the top and bottom of the iron, as shown in Figure 1.

From the foregoing description it is obvious that a very simple and efficient iron has been provided, which, while it is secured to the crate by rivets, is not dependent upon the same and will efficiently hold the sides of the crate together in instances where the rivets might become sheared or loosened, or the sides of the crate become split horizontally.

It will further be seen that flanges 4 will, in the stacking of the crates, one upon the other, engage the flanges of the adjacent irons to effect a uniform stacking of the crates and protect the top and bottom edges of the wooden sides. The lower ears 6 hav-

ing their adjacent sides converging toward the inner edge of the lower flange 4, serve to engage the offset projection 5 of the adjacent iron, thus protecting the inner sides of the 5 crate in the stacking, and further effecting uniformity of the same.

I claim:

A corner iron for a crate having an open top and bottom, said corner iron being 10 formed of a single blank of material and having a body portion extending around the outside of the corner of the crate, said body portion having an integral inwardly extending flange projecting across the top of the 15 adjacent sides of the crate, said flange hav-

ing three lips cut therefrom forming outer lips and an inner lip, the outer lips being turned downwardly to form attaching ears positioned on the inner side of the crate, fastening means extending through such ears 20 into the body portion of the corner iron, the third of said ears being upturned and forming an angularly constructed guiding projection.

In testimony that I claim the foregoing 25 I have hereunto set my hand at Milwaukee, in the county of Milwaukee and State of Wisconsin.

WILLIAM C. KRAUSE.
